UNITED STATES PATENT OFFICE.

FREDERICK D. McGINLEY, OF PLEASANT BEACH, NEW YORK, ASSIGNOR OF ONE-HALF
TO LUCIUS L. LACEY, OF SYRACUSE, NEW YORK.

CAR REPLACER.

Application filed August 31, 1922. Serial No. 585,383.

To all whom it may concern:

Be it known that I, FREDERICK D. McGINLEY, a citizen of the United States, and a resident of Pleasant Beach, in the county of Onondaga, in the State of New York, have invented new and useful Improvements in Car Replacers, of which the following, taken in connection with the accompanying drawings, is a full, clear, and exact description.

10 This invention relates to a device for replacing derailed cars and is commonly known as a car replacer, adapted to be placed alongside of the rail or rails in proximity to the derailed wheels of the car, for 15 the purpose of raising and guiding the wheels over and upon the rails as the car is propelled along and upon the replacer.

The main object is to provide a device of this character which may be used at either 20 side of either rail, according to the position of the derailed wheels of the car relatively to said rails, by simply reversing certain removable parts of the replacer.

Another object is to provide the replacer 25 with laterally yielding guide ribs, or supplemental rails to cooperate with a relatively fixed wheel-deflecting rib for carrying the displaced wheels upwardly and laterally as they are drawn upon the replacer and 30 deflected laterally thereby toward the rail by the relatively fixed rib.

Other objects and uses relating to specific parts of the device will be brought out in the following description.

35 In the drawings:

Figure 1 is a top plan and Figure 2 a side elevation of a car replacer embodying the various features of my invention, a portion of one of the track rails being shown 40 in Figure 1.

Figure 3 is a longitudinal vertical sectional view taken on line 3—3, Figure 1.

Figures 4—5—6—7 and 8 are transverse vertical sectional views taken respectively 45 on lines 4—4, 5—5, 6—6, 7—7 and 8—8, Figure 1.

Figure 9 is a side elevation of a detached adjustable abutment for engaging the web of the rail.

50 As illustrated, this device comprises a main supporting frame or bed-plate —1—, a leader-plate —2—, supplemental guide rails or ribs —3—, a clamping bolt —4—, a stop-plate or abutment —5—, and a detent —6—, all of which parts are constructed

and assembled in the manner presently described.

The central portion of the main body or bed-plate —1— is elevated some distance above the horizontal plane of its opposite ends and is substantially horizontal when the device is adjusted for use, one end of said bed-plate, upon which the derailed wheels first enter in replacing the car, and hereinafter termed "the leader end" is inclined 65 upwardly to the plane of the central horizontal portion, and is provided with a correspondingly inclined upper face —7—, for receiving and supporting the leader plate —2—, said inclined surface —7— being substantially flat transversely to permit the leader-plate —2— to move across the surface thereof.

The lower face of the outer end of the inclined portion of the bed-plate is substantially horizontal and adapted to rest upon the ties at the inner or outer side of the track rail, according to the position of the derailed wheels, and is also provided with spurs —8—, adapted to imbed themselves 80 in the tie to hold the bed-plate against slipping when propelling the car upon the replacer.

This bed-plate is also provided with laterally and downwardly projecting legs or 85 feet —9— in longitudinally spaced relation between the opposite ends thereof to rest against the flange and web of the track rail, as —A—, to assist in supporting the bed-plate in proper relation to the rail upon 90 which the derailed wheels of the car are to be replaced.

The lower face of the front end of the bed-plate is substantially flat and horizontal to rest upon the stop-plate or abutment 95 —5— and to permit the latter to be adjusted rotarily to one side or the other as may be required for setting the device for replacing the car.

The bed-plate is preferably made of cast 100 metal such as malleable iron or equivalent strong material, and is provided with a central, longitudinally extending guard rib —10— and relatively short guide ribs or flanges —11— in transversely spaced relation to and at opposite sides of the central rib —10—, which extends from the upper front end of the leader-plate —2— to the front end of the bed-plate and is gradually widened at its front end to form a 105 raised 110

boss —12—, having rearwardly converging sides —13— merging with corresponding sides of the remaining portions of the guard rib —10—, for engaging and deflecting the 5 displaced car wheel laterally toward the rail upon which it is to be replaced as it is drawn forwardly upon the replacer.

The guide ribs —11— are spaced some distance apart from the adjacent sides of the 10 central guard rib —10— to form lengthwise channels in which the flange of the displaced car wheel is adapted to travel, said guide rib —11— being extended forwardly a short distance from the front upper end of 15 the leader plate —2—, and into close proximity to the rear ends of the laterally movable guide ribs or supplemental rails —3— in longitudinal alignment therewith, shown in Figure 1.

20 The leader-plate —2— is inclined forwardly and upwardly and rests upon the inclined surface —7— and is centrally pivoted near its rear end to the adjacent portion of the bed-plate by a pivotal stud —14— to permit 25 it to swing laterally across and upon the inclined surface —7— until limited by the stops —15—, projecting upwardly from opposite sides of the bed-plate and preferably formed integral therewith, said stops 30 being located near the front upper end of the leader-plate —2—.

This leader-plate is provided along its opposite lengthwise edges with upwardly projecting flanges —16— in transversely spaced 35 relation, to form an intervening lengthwise channel from end to end thereof, these ribs —16— converging from their rear ends forwardly, and their front ends are spaced apart a distance corresponding substantially 40 to the distance between the central guard rib —10— and supplemental movable rails —3—.

The stops —15— are arranged a sufficient distance apart to permit the front end of either rib —16— to be moved into registration 45 with the rear end of the central fixed rib —10—, while the other rib —16— will then be registered with one of the guide ribs —11—, that is, when one of the guide ribs —16— of the leader-plate —2— is registered 50 with one of the ribs —11—, the other guide rib —16— will be registered with the rear end of the central rib —10—, and in either position of adjustment of the leader-plate —2— against one or the other of the stops —15—, the rib —11—, which is registered with one 55 of the ribs —16— will form a continuation of the latter and is in sufficiently close proximity thereto to permit the wheel of the car to ride from one to the other as it is drawn 60 upon the elevated portion of the replacer.

The supplemental guide rails —3— rest upon the upper horizontal surface, as —17—, of the bed-plate —1— in transversely spaced 65 relation to and at opposite sides of the central rib —10—, and are pivoted near their

rear ends to the bed-plate by pivotal studs —18— extending downwardly through suitable openings in the bed-plate, so as to hold the rear ends of the supplemental rails —3— in alignment with the front ends of the relatively short guide ribs —11—.

These supplemental rails —3— extend forwardly in proximity to the opposite rearwardly converging sides —13— of the boss —12— and their front ends are preferably 75 deflected downwardly and provided with laterally projecting horizontal feet —19— resting upon a horizontal portion —20— of the bed-plate, for lateral movement thereon about the axes of their respective pivotal 80 studs —18—, the lower front ends of said rails —3— being yieldingly connected to each other by means of a coil spring —21— which extends through a transverse opening —22— in the lower portion of the rib —10— 85 just at the rear of the boss —12—.

The clamping bolt —4— is passed through a transverse opening —23— in the base-plate —1—, preferably near the forward end thereof, and is provided at one end with a hook shaped portion —24—, adapted to engage the top or ball of the rail, the other end of the bolt being threaded for engagement with a nut —25—, by which the plate —1— may be drawn edgewise or laterally 90 into the desired proximity to the rail upon which it is desired to replace the car wheels, the opening —23— being elongated vertically to allow the bolt to be properly adjusted for rails of different heights. 95

100 The detent, or pawl —6—, is hinged by a pivotal bolt —26— to the under side of the central portion of the leader plate —2— to permit its free end to swing laterally in opposite directions in an opening —27— in the plate —1— into and out of engagement with the opposite side walls of said opening, for holding the plate —2— in its adjusted position, against one or the other of the stops —15—, and thereby to hold either of the flanges —16— in alignment with the corresponding flanges —11— and —3—, according to the position of the replacer with reference to the wheels which are to be replaced upon the rails. 110

115 The stop plate or rest —5— is engaged with the under side of the front end of the base plate —1— for supporting the same, and is provided with a reduced circular boss —28— projecting upwardly therefrom, near one end, for engagement in a similar opening —29— in the underside of the front end of the base plate, to constitute a pivotal connection between the plate —5— and base plate, whereby the latter may be swung horizontally through an arc of substantially 180 degrees for engagement with a rail at either side of the replacer, said boss —28— being provided with an annular groove —30— for receiving 120

the inner end of a retaining screw —31—, by which the plate —5— is held in operative relation to the base plate, without in any way interfering with the free rotary movement of the rest plate.

- 5 The end of the longer arm of the plate —5— is adapted to abut against the web of the rail, as —A—, and is provided with a foot —32— adapted to rest upon the base flange of the rail, while the opposite end or shorter arm of the same plate is provided with a somewhat lower foot —33— adapted to rest upon the tie which supports the rail, thereby establishing a firm support for the 10 front end of the replacer, while it is being used for replacing the wheels of a car upon the rails.

15 The rearward and downward inclination of the rear end of the base plate —1— and leader plate —2— brings the rear end edges of those parts close to the surface of the ties and base of the rail upon which it is desired to replace the wheels of the car, so that the 20 wheels may ride more easily from the ties upon the leader plate with the flange of the wheel at the inside of one or the other of the flanges —16— and the tread of the wheel resting upon the corresponding flange of the leader plate, the rear ends of said flanges —16— being extended rearwardly some distance beyond the intermediate portion of the web of the plate —2—, to facilitate the riding of the tread of the wheel upon the upper edge of the flanges when being propelled 25 upon the replacer.

30 These replacers are preferably used in pairs, to receive the car wheels on the opposite ends of the same axle, and therefore one of them would be used at the inside of one rail and the other at the outside of the opposite rail, and inasmuch as the flanges of the wheels are adapted to ride along the inner sides of the rails, it becomes necessary to elevate the displaced wheels which are at 35 the outside of the track, to a greater height than those at the inside of the track, and for this purpose the center flange —10— is of sufficiently greater height than that of the side rails —3— to elevate the flanges of the 40 wheels riding thereon above the ball of the rail upon which the wheels at the outside of the track are to be replaced, while the height of the side rails —3— are only slightly higher than the rails, to allow the tread of the 45 wheels at the inside of the rail to ride over and upon the ball of the rail.

Operation.

50 Assuming now that the replacer as shown in Figure 1 is to be used for replacing car wheels which have been displaced at the inner side of the rail, and that it is properly set and clamped in that position with the forward end of the leader plate —2— adjusted toward the rail and locked in that

position by the locking member —6— against the adjacent stop —15—, so that the adjacent flanges —16—, —11— and —3— will be in alignment, and the other flange —16— will be aligned with the center flange 70 —10—, it being understood that this positioning of the replacer will bring its rear end into close proximity to the displaced wheel.

75 Then by propelling the car forwardly, the tread of the wheel will ride upon the flange —16— nearest the rail, while the flange of the wheel will ride upon the upper face of the web of the plate —2— between the flanges, and as the car wheel is propelled up 80 the incline of the plate —2—, its flange will be directed between the flange —10— and flanges —11— and —3— nearest the rail, while the tread of the wheel will ride upon the flanges —11— and —3— until the flange 85 of the wheel encounters the adjacent laterally inclined face —13— of the boss —12—, which will cause a corresponding lateral shifting movement of the car wheel against the adjacent flange —3—, which is yielding, 90 sufficient to bring the tread of the wheel directly over the ball of the rail.

95 During this operation the other replacer which has been previously placed in operative position at the other side of the outer rail, will receive the other car wheel and its tread to ride upon the other flange —16— of the plate —2— and thence upwardly upon the higher center flange —10— of the base plate, thereby elevating the outer wheel a 100 sufficient distance to allow its flange to pass over the ball of the adjacent rail when the other wheel is crowded laterally toward the corresponding rail by its engagement with the laterally inclined face —13—, the effect 105 of the use of the two replacers simultaneously, one at the inside and one at the outside of the track, being to simultaneously replace both wheels of the same axle upon the ball of the rail.

110 It is evident from the symmetrical arrangement of the side flanges —3— at opposite sides of the center flange —10—, together with the lateral adjustment of the leader plate —2— and detents —5— and —6—, that the replacers may be used at either side of either rail to replace cars by propelling them in either direction lengthwise of the rails.

115 What I claim is:

120 1. A car replacer comprising a base plate having a central lengthwise flange and opposite side flanges in spaced relation thereto, the central flange being of greater height than the side flanges, and a leader plate pivotally mounted upon the base plate, to move laterally, and provided with guide flanges movable into and out of registration with those on the base plate.

125 2. A car replacer comprising a base plate 130

- having a central lengthwise flange and opposite side flanges in spaced relation thereto, the central flange being of greater height than the side flanges, and a leader plate pivotally mounted upon the base plate, to move laterally, and provided with guide flanges movable into and out of registration with those on the base plate, and means for holding the leader plate in its adjusted position.
10. 3. A car replacer comprising a base plate having a central lengthwise flange and opposite side flanges in spaced relation thereto, the central flange being of greater height than the side flanges, and a leader plate pivotally mounted upon the base plate, to move laterally, and provided with guide flanges movable into and out of registration with those on the base plate, the side flanges of the base plate being movable laterally relatively to the center flange.
15. 4. A car replacer comprising a base plate having a central lengthwise flange and opposite side flanges in spaced relation thereto, the central flange being of greater height than the side flanges, and a leader plate pivotally mounted upon the base plate, to move laterally, and provided with guide flanges movable into and out of registration with those on the base plate, the side flanges of the base plate being movable laterally relatively to the center flange, and means for yieldingly urging the side flanges of the base plate toward the center flange.
20. 5. A car replacer comprising a base plate having a central lengthwise flange and opposite side flanges pivoted thereto to swing toward and from the center flange.
25. 6. A car replacer comprising a base plate having a lengthwise flange and opposite side flanges mounted thereon for lateral movement and spring-pressed toward the center flange, said center flange having opposite laterally diverging faces adapted to be engaged by the flange of the car wheel for shifting the latter laterally as it is rolled thereagainst in the direction of divergence.
30. 7. A car replacer comprising a base plate, a rail engaging member reversibly mounted upon the underside of one end of the base plate for engaging the web and base flange of a rail at either side of the base plate to

hold said base plate against lateral movement toward the rail, and a leader plate on the opposite end of the base plate, inclining upwardly toward the first named end, and means for clamping the base plate to the rail.

8. A car replacer comprising a base plate having a longitudinally inclined surface at one end, a leader plate pivotally mounted upon said inclined surface to swing laterally, stops on the base plate at opposite sides of the leader plate, to limit the lateral movement of said leader plate in either direction, and a reversible detent on the leader plate cooperating with portions of the base plate for holding the leader plate against either of said stops.

9. A car replacer comprising a base plate having a fixed lengthwise flange widened at its forward end, and an additional lengthwise flange pivotally mounted upon the base plate, for lateral movement toward and from the fixed flange, and an upwardly and forwardly inclined leader plate mounted on the rear end of the base plate.

10. A car replacer comprising a base plate having a central lengthwise flange widened at its forward end, and opposite side flanges mounted on the base plate and extending forwardly, and a leader plate pivotally mounted upon the rear end of the base plate for lateral movement, and provided with opposite lengthwise flanges movable into and out of registration with the rear ends of the first named flanges.

11. A car replacer comprising a base plate having a central lengthwise flange widened at its forward end, lengthwise side flanges pivotally mounted upon the base plate at opposite sides of the central flange to swing laterally, a spring connecting said side flanges and a leader plate pivotally mounted upon the rear end of the base plate for lateral swinging movement, and provided with opposite side flanges movable into and out of registration with the first named flanges.

In witness whereof I have hereunto set my hand this 23rd day of August 1922.

FREDERICK D. McGINLEY.

Witness:

H. E. CHASE.
